SILO CHUTE

William W. Gurney, Winona, Minn., assignor to
Madison Silo Company, Madison, Wis., a corporation of Wisconsin

Application April 29, 1937, Serial No. 139,790

8 Claims. (Cl. 72—6)

My invention relates to silos, and more particularly to chutes therefor.

By way of explanation, it is the practice to construct one type of silo of concrete staves interfitting at their edges and concrete door frames interfitting at their edges with the adjacent staves and with each other.

The primary object of my invention is to equip a silo of the above identified type with a metal chute enclosing the door frames of the same and jointed to the silo structure so as to exclude air and rain at its juncture therewith.

Another object is to equip a silo of this construction with a sectional chute adapted to be built up section by section as the building of the silo progresses, the sections interfitting with one another and with the staves and door frames so that said sections are supported entirely by the silo structure and each other, thereby obviating the necessity for using bolts, angleirons, hangers, or similar attaching instrumentalities.

Still another object of my invention is to provide a chute for such silos which is strong, durable, practically impervious to water and to rain, easily assembled as regards its component parts, readily incorporated with the silo structures and comparatively inexpensive to manufacture.

Other and subordinate objects will become readily apparent from the following description and claims when read with reference to the drawings, accompanying and forming part of this specification.

In said drawings:

Figure 1 is a view in side elevation of a silo of the type with which my invention is particularly concerned and equipped with a chute constructed in accordance with my invention.

Figure 2 is a fragmentary view partly in vertical section and partly in elevation taken on the line 2—2 of Figure 1, looking in the direction indicated by the arrows and drawn to an enlarged scale.

Figure 3 is a view in transverse section taken on the line 3—3 of Figure 2, looking downwardly.

Figure 4 is a fragmentary view in vertical transverse section taken on the line 4—4 of Figure 3.

Figure 5 is a fragmentary view in rear elevation of mating sections of the chute.

Figure 6 is a fragmentary view in transverse section of a modification of the invention, and

Figure 7 is a similar view of another modified form of the invention.

Referring to the drawings by numerals, and first with general reference to the type of silo

with which my invention is particularly concerned, such silos are constructed by building up the aforementioned concrete staves, designated 1, in tiers 2, to form a circular structure, the staves of alternate tiers being staggered with respect to those of intermediate tiers as will be understood.

The door frames 3, which are rectangular in shape, are disposed on top of each other in edge to edge relation between two opposite tiers, as shown in Figure 2, and keyed to, or interfitting with said opposed tiers by means of vertical tongue and groove connections 4 and 5 between the sides of said frame and the staves 1 of said tiers respectively. It may be mentioned at this point, that the staves 1 of each tier 2 are interfitting with those of the adjacent tiers in the same manner as the doorframes 3 and the adjoining tiers.

The described silo structure is reinforced by the usual vertically spaced reinforcing hoops 6, as shown in Figure 1, which, it may be mentioned, are disposed intermediate the doorways represented at 7 or in other words, opposite the junctures of the doorframes 3.

According to my invention the described silo is equipped with a sheet metal chute 9, preferably of steel, comprising sections 10 of substantially the same height as the doorframes 3 and of U-shape in cross section, arranged one on top of the other in edge to edge relation, to form a continuous conduit covering as many doorways 7 as desired. The mating top and bottom edges of the sections 10 are jointed together by means of interfitting edge beads, the top of each section 10 being provided with a small edge exterior bead 11 and the bottom edge with a larger bead 12 overlapping the smaller bead 11 of the subjacent section.

The vertical edges of each section 10, as best shown in Figure 3, are rolled, or crimped, to provide a pair of longitudinally extending marginal beads 13 on said edges, respectively, interposed between the aforementioned tongue and groove connections 4 and 5, whereby said sections are interfitting with said frames and the adjacent tiers 2 to be supported thereby and also by each other, as will be clear. Each section 10 at the corners thereof, formed by the vertical and horizontal edges, is notched, as shown at 14 in Figure 5, so that the notches of mating sections form recesses, as at 15, for accommodating the appropriate hoop 6 or in other words clearing the latter. The top of the chute 9 may be closed in any suitable manner as represented at 15.

It will be understood that the before mentioned tongue and groove connection, 4 and 5, may be of different shapes in different makes of staves. In Figure 3, said connection is shown as segmental and the beads 13 are accordingly correspondingly shaped. However, it is to be understood that said beads may vary in cross-sectional contour according to the variations in the shape of said connection. For instance, as shown in Figure 6, the tongue 16 and the groove 17 are semicircular and the bead 18 correspondingly shaped, whereas, in Figure 7, the tongue 19 and groove 20 are tapered and the bead 21 correspondingly formed.

The foregoing description will, it is believed, suffice to impart a clear understanding of the construction and advantages of my invention.

It is to be understood, however, that the present disclosure is illustrative rather than restrictive, and that modifications, other than those disclosed, may be resorted to without departing from the inventive concept, hence, right is herein reserved to such other modifications of details described as fall within the scope of the appended claims.

What I claim is:

1. The combination with a silo having superposed door frames, of a sheet metal chute having vertical side edges built into the wall of the silo on opposite sides of said frames respectively.

2. The combination with a silo having superposed door frames, of a sheet metal chute having vertical side edges built into the wall of the silo upon opposite sides of said frames, respectively, and comprising sections superposed on one another in edge to edge interfitting relation.

3. The combination with a silo having superposed door frames, and hoops surrounding the silo intermediate said frames, respectively, of a sheet metal chute having vertical side edges built into the wall of the silo upon opposite sides of said frames, respectively, and comprising sections superposed on one another in edge to edge interfitting relation, said sections being of substantially the same length as the door frames, respectively, to register therewith, and having opposed notched corners for fitting over said hoops.

4. The combination with a silo having superposed door frames, of a sheet metal chute having vertical side edges built into the wall of the silo on opposite sides of said frames, respectively, said edges and walls having vertically extending mating key parts within said wall coating to lock said edges in said wall.

5. The combination with a silo having superposed door frames, of a sheet metal chute comprising vertical side edges built into the wall of said silo upon opposite sides of said frames, respectively, and comprising sections superposed in edge to edge mating relation, said sections comprising edge beads at their mating edges interfitting in interlocking relation.

6. The combination with a silo having a cement wall and superposed cement door frames, of a sheet metal chute having vertical side edges built into said wall upon opposite sides of said frames, respectively, and having a pair of marginal beads extending along said edges, respectively, within said wall.

7. The combination with a silo having a cement wall and superposed cement door frames, of a sheet metal chute having vertical side edges built into said wall upon opposite sides of said frames, respectively, and having a pair of marginal beads extending along said edges, respectively, within said wall, said chute comprising sections superposed one upon another in edge to edge interfitting relation.

8. The combination with a silo having a cement wall and superposed cement door frames, of a sheet metal chute having vertical side edges built into said wall upon opposite sides of said frames, respectively, and having a pair of marginal beads extending along said edges, respectively, within said wall, said chute comprising sections superposed one upon another in edge to edge mating relation, adjoining upper and lower sections at their mating edges being provided with a pair of interfitting beads, the bead on the upper section overlapping the bead on the lower section.

WILLIAM W. GURNEY. 45
